UNITED STATES PATENT OFFICE.

GEORGE W. MCGILL, OF NEW YORK, N. Y.

METALLIC FASTENER.

SPECIFICATION forming part of Letters Patent No. 252,685, dated January 24, 1882.

Application filed December 8, 1881. (No model.)

To all whom it may concern:

Be it known that I, GEORGE W. MCGILL, a citizen of the United States, residing at New York city, in the county of New York and State of New York, have invented certain new and useful Improvements in Metallic Fasteners; and I do hereby declare the following to be a full, clear, and exact description of the invention, such as will enable others skilled in the art to which it appertains to make and use the same, reference being had to the accompanying drawings, making part of this specification, and to the figures and letters of reference marked thereon, in which similar letters of reference indicate corresponding parts.

My invention relates to an improved mode of constructing the metallic fastener for which United States Letters Patent No. 249,850 were issued to me November 22, 1881, and has for its object the production of a cheap and convenient fastener for binding together a number of pieces of any kind of textile fabric and attaching marking tickets or tags to the same without the fiber of the material bound or ticketed being cut or injured by the operation.

The object of my improvement is to cheapen the cost of the manufacture of the fastener, which end is secured by using ordinary pins for its penetrating or fastening prongs, and adapting its head to receive and hold the same in proper parallel position at right angles thereto, thereby obviating the expense and labor of producing new and special machinery to make the shanks or prongs, and economizing considerably on the cost of such shanks.

The fastener is constructed as follows: Its shanks or prongs consist of two or more separate pins, A A, of ordinary construction, such as shown in Figure 1. These pins are inserted in a metal washer, B, provided with pin-holes b b for their reception.

Figs. 2 and 4 are top or plan views of the washer. Fig. 2 shows the washer blanked flat, and Fig. 4 represents it with its center concaved. Fig. 3 is a vertical cross section of Fig. 2, taken on line x x of that figure. Fig. 5 is a similar view, but represents the pin-holes b b pierced or drawn in a manner to produce the tubular sleeves b² b² on the under side of the washer to assist in holding the pins in firm vertical position.

Fig. 4^a is a vertical cross-section of Fig. 4 taken on the line y y of that figure. The pin-holes b b are countersunk so that the top of the heads of the pins will come even with the top of the central portion of the washer. The pins A A are inserted in the washer B, as shown in Fig. 6, which is a top view, in perspective, of the pins and the washer so connected. The washer B is now covered by a metal-button cap, C, such as shown in Fig. 7, which represents the cap in reversed position, and the cap is closed upon the washer by an ordinary button-capping machine in the usual manner, thereby locking the washer and cap together and securing the pins A in their pin-holes b, as shown in Fig. 8, which is a bottom view, in perspective, of the fastener so constructed, and in Fig. 9, which is a vertical cross-section of Fig. 8.

Fig. 10 represents a vertical cross-section of the fastener, having its washer B fashioned with a concaved center, as shown in Fig. 4. The object of this form of washer is to cause the closed-in flange of the cap to come even with the bottom surface of the washer, as shown in said Fig. 10.

Fig. 11 is a plan view of a packing-disk, D, which is placed in the sunken center of the washer to pack the pin-heads firmly in their countersunk holes, as shown in the sectional Fig. 10.

A modification in the construction of the device is shown in the sectional Fig. 13, the cap C being shown in reversed position and its center struck up or convexed and provided with pin-holes b b, in which the pins A A are inserted, their heads being covered by a crown-piece, D', corresponding in shape to the bottom of the cap C, and over the rim or edge of which the flange of the cap is closed down, so as to secure all the parts of the fastener in proper position. Instead of the central part of the reversed cap being concaved, as shown in Fig. 10, it may be pierced by a large center hole, and the shank-pins A inserted in pin-holes pierced on each side of the large center hole, and held therein by closing the flange of the cap down directly upon their heads, thereby producing a fastener with a pierced or ring-shaped head, to admit of tags and of such like being readily tied in the same.

Fig. 12 is a side view of the fastener binding together several sheets of material.

In using ordinary pins for the fastener-prongs, as herein described, I first slightly anneal the same, so as to remove from them some of their stiffness or elasticity.

I do not claim herein anything shown or described by me in my said United States Letters Patent No. 249,850, of November 22, 1881.

10. I have previously made, in accordance with Letters Patent heretofore granted to me, metallic fasteners having their penetrating prongs or shanks formed from round wire, pin-pointed and provided with integral heads; and I 15 therefore do not broadly claim herein a fastener having wire shanks provided with integral heads; but

What I do claim, and desire to secure by Letters Patent, is—

1. A metallic fastener having its separate 20 shanks formed of round wire with their penetrating ends pin-pointed and their opposite ends pin-headed, as shown, and inserted in the countersunk holes *b b* of the washer or cap, and secured therein by the washer and cap being connected together, as shown, substantially as and for the purposes described.

2. In combination with the separate pin-shanks A, washer B, and cap C, the packing-disk D, inserted between the washer and cap 30 above the pin-heads, substantially as and for the purposes described.

In testimony whereof I hereto affix my signature in the presence of two witnesses.

GEORGE W. MCGILL.
